UNITED STATES PATENT OFFICE.

CHARLES W. ROEPPER, OF ALLIANCE, OHIO.

BRAKE-SHOE.

SPECIFICATION forming part of Letters Patent No. 423,818, dated March 18, 1890.

Application filed May 31, 1889. Serial No. 312,772. (No model.)

To all whom it may concern:

Be it known that I, CHARLES W. ROEPPER, a citizen of the United States, and a resident of Alliance, county of Stark, and State of Ohio, 5 have invented certain new and useful Improvements in Brake-Shoes, of which the following is a specification, the principle of the invention being herein explained and the best mode in which I have contemplated applying that principle, so as to distinguish it from other inventions.

My invention has for its object an improvement on the form of brake-shoe commonly known as the "Ross" shoe. It is well known 15 to those skilled in the art of brake-shoe manufacture that it frequently happens, owing to peculiar and varying conditions in the use of brake-shoes, due to peculiarities in the mode of hanging the shoes, or to varying qualities 20 of material in the shoes and tires used, or to unskillfulness in use and operation of the brakes, or owing to other causes, some known and others indeterminate, except by actual trial and experiment, that the common Ross 25 form of shoe fails at times to fulfill all the varying needs of railroad service. It is to supply these lacking requisites in the Ross shoe that my several forms of shoe described in this and other applications simultaneously 30 pending have been designed. In this form of shoe I provide for a reduction of the flange-contacting portion of the shoe, together with an equal reduction in the rib portion of the shoe that has contact with the neck of the 35 tire, while at the same time I provide a contacting portion for the inner tread of the wheel whereby to balance and correct the inequalities of the wheel which frequently occur by the time the shoe has been partially 40 worn down.

Referring to the drawings, Figure 1 is a face view of one form of shoe. Fig. 2 is a face view of a second form of shoe. Fig. 3 is a central sectional view of Fig. 1, taken on 45 the central dotted line thereof. Fig. 4 is a transverse sectional view of Fig. 2, taken on the dotted line of that figure.

This form of brake-shoe may be briefly described as consisting of three parts or portions: first, the outer tread-contacting portion A, that is in continual contact with the

wheel whenever the brake is applied, said portion being slightly beveled from its inner edge outwardly, in order to assist in dressing down the outer edge of the wheel, and having 55 a continuous, uninterrupted, or unbroken face the length of the brake-shoe; second, the flange-contacting portion B, that is provided with a groove b, in which fits the flange of the wheel when the brake-shoe is in use, the 60 face or wall of said groove being in contact with the flange of said wheel; third, the intermediate portion or inner tread-contacting portion C, that engages with the inner tread portion of wheel in the form shown in Fig. 2, and also 65 in the form shown in Fig. 1, after the shoe has become partially worn down. The face of this portion of the shoe is not continuous, but is broken by the recess portion c, that is depressed from the uplifted or end portions c'. 70 It will be noticed that the flange-contacting portion B is of less length than the length of the brake-shoe, and that contact portion of the intermediate portion C is also less than the length of the brake-shoe, the contact portions of these two portions being of about 75 equal length and lying in different transverse planes. Openings c² are cut through the face of the recess to permit the wearings or grindings caused by the contact of the shoe and 80 the wheel to pass out and free themselves from the shoe instead of lodging and collecting in the latter. A rib D forms the outer face or wall of the groove and has contact 85 with the neck of the wheel.

The broad feature of providing openings in the inner tread portions of the shoe, shown and described in this application, I do not claim herein, as I claim this feature in another application simultaneously pending 90 herewith—viz., application Serial No. 312,777.

The wear of the rail against the wheel is so considerable that it is not necessary to form the inner tread-contacting portion C as long as the outer tread-contacting portion, and 95 therefore it is that I shorten the same. The recess being formed between the two disconnected portions of said inner tread-contacting portions also has a tendency to prevent the skidding of the wheels and consequent 100 injurious flattening and wearing of the same.

I designate that portion of the shoe that

engages or has contact with the flange of the wheel as the "flange-contact" or "flange-contacting" portion, while that portion of the shoe that is opposite to and covers or may be 5 adapted to have engagement with the inner tread portion of the wheel, which is that portion of the wheel most likely to be worn down by engagement with the rail, I designate as the "inner tread contact" or "contacting portion" of the shoe. The outer tread contact or contacting portion of the shoe is intended to signify that portion of the shoe lying outside of the inner tread-contact portion, said outer tread-contact portion adapted 10 to have engagement with the outer tread portion of the wheel.

The foregoing description and accompanying drawings set forth in detail mechanism in embodiment of my invention. Change may 20 be made therein provided the principles of construction respectively recited in the following claims are employed.

I therefore particularly point out and distinctly claim as my invention—

- 25 1. In a brake-shoe, the combination, with a flange-contact portion formed in one continuous unbroken piece and an outer tread-contact portion, of an inner tread-contact portion, the contacting face of said flange-contact portion and said inner tread-contact portion being of less length than the outer tread-contact portion, substantially as set forth.
- 30 2. In a brake-shoe, the combination, with a continuous and unbroken flange-contact portion and an outer tread-contact portion, of an inner tread-contact portion formed in two longitudinally-disconnected portions, a re-

cess being formed between the two, the collective length of said inner tread-contact portion and the length of said flange-contact portion being substantially equal, substantially as set forth.

3. In a brake-shoe, the combination, with an outer tread-contacting portion and an inner tread-contacting portion formed in two 45 longitudinally-disconnected portions, said latter portions together being of less length than the outer tread-contacting portion, of a groove adapted to receive the car-wheel flange, the contacting-face of said groove of less length 50 than the face of the outer tread-contacting portion, the greater portion of said groove-contacting face and said disconnected inner tread-contacting faces lying in different transverse planes, substantially as set forth.

4. In a brake-shoe, the combination, with an outer tread-contacting portion and inner tread-contacting portion lying in a plane depressed from that of the outer tread-contacting portion, whereby it engages with the 60 tread of the wheel as the brake-shoe becomes worn, said inner tread-contacting portion formed in two longitudinally-disconnected portions, a recess being formed between the two, of a flange-contacting portion provided 65 with a groove adapted to receive the wheel-flange, substantially as set forth.

In testimony that I claim the foregoing to be my invention I have hereunto set my hand this 25th day of May, A. D. 1889.

CHARLES W. ROEPPER.
